(57) **CLAIM**

The ornamental design for a mobile computer, as shown and described.

DESCRIPTION

FIG. 1 is a perspective view of a mobile computer showing my new design,

FIG. 2 is a perspective view of the mobile computer of FIG.

1 shown in an alternative configuration of use thereof,

FIG. 3 is a perspective view of the mobile computer of FIG.

1 shown in an alternative configuration of use thereof,

FIG. 4 is a rear elevational view thereof,

FIG. 5 is a front elevational view thereof,

FIG. 6 is a top plan view thereof,

FIG. 7 is a bottom plan view thereof,

FIG. 8 is a left side elevational view thereof,

FIG. 9 is a right side elevational view thereof,

FIG. 10 is a top plan view of the mobile computer of FIG.

1 shown in an alternative configuration of use thereof,

FIG. 11 is a front elevational view of the mobile computer of FIG. 1 shown in another alternative configuration of use thereof,

FIG. 12 is a top plan view in the state of being folded thereof,

FIG. 13 is a left side elevational view in the state of being folded thereof; and,

FIG. 14 is a right side elevational view in the state of being folded thereof.

The broken lines in the drawings depict portions of the mobile computer that form no part of the claimed design.

1 Claim, 7 Drawing Sheets
